[57] **ABSTRACT**

Alternative lifting means is provided for the work supporting horn of a fastener inserting machine so that the horn may be vertically adjusted readily whenever the nature of the work being supported does not allow such adjustment in normal fashion, as when the heel of a boot is being supported and the bottleg covers the normally exposed horn structure against access.

HORN LIFTING MEANS FOR FASTENER INSERTING MACHINE

BACKGROUND OF THE INVENTION

Fastener inserting machines of the sort employed for attaching shoe heels characteristically include a vertically adjustable horn for supporting a shoe at the heel portion during fastener insertion as seen in U.S. Pats. No. 2,240,429 and No. 2,793,364. Both of these patents show a gooseneck form of horn, but other horn forms are used as needed, and particularly axially standing horns as in U.S. Pat. No. 3,241,225. The latter type of horn is needed in an extended length when boots are being handled, but difficulty is encountered in adjusting the horn vertically to handle a boot because the depending bootleg covers the lower portion of the horn structure at which it is normally grasped for adjustment, and the recent trend toward boots has made this difficulty extremely troublesome, especially in shoe repair operations.

SUMMARY OF THE INVENTION

According to the present invention an alternatively accessible lifting means is associated with the horn structure of a fastener inserting machine so that upward vertical adjustment of the horn is still readily accomplished whenever access for lifting it in normal fashion is obstructed. The alternative lifting means provided takes the form of a pull rod spaced in parallel relation to the vertical adjustment axis of the horn and engageable with a lateral arm attached at the lower end of the horn for lifting the same and thereby causing the horn to move upward through its adjustment range whenever desired. The pull rod is slidably mounted on the fastener inserting machine and is arranged to engage the lateral arm only for lifting the same so as to be free for return by gravity to a normally retracted position whenever released and to remain retracted whenever the horn is lifted otherwise.

DESCRIPTION OF THE DRAWINGS

FIG. 1 is a perspective illustration of the arrangement of a horn lifting means embodying the present invention in a fastener inserting machine;

FIG. 2 is an exploded side elevation of intermediate parts of the horn structure; and

FIG. 3 is a fragmentary side elevational detail, partly in section, showing the arrangement of the pull rod for engaging the lateral arm attached to the lower end of the horn.

DESCRIPTION OF THE PREFERRED EMBODIMENT

The fastener inserting machine illustrated in FIG. 1 is of the general type shown in the previously noted prior U.S. Pat. No. 3,241,225 by which fasteners are cyclically formed from a continuous length of wire and inserted in work to be secured at an operating head 10 that is mounted on an upper frame bracket 12 above a shelf 14 that serves as a working surface and forms the top of a base frame structure 16.

In order to provide adequate space for handling boots (as at B in FIG. 1), the base frame structure 16 is lessened in height and the upper frame bracket 12 is lengthened correspondingly to increase the neck

dimension at which the operating head 10 is disposed above the shelf 14. Such dimensional modification of the frame components, however, is limited by disadvantage in raising the operating head 10 appreciably above its normal elevation and by restriction of the extent to which shelf 14 may be lowered and still leave room for the drive and related operating mechanisms that are housed within the base frame structure 16 (compare prior Pat. No. 2,793,364). Accordingly, when boots are being handled a considerable percentage of them will have leg portions of such length as to interfere with normal manipulation of the horn structure provided for supporting the work during fastener insertion, as indicated generally at 18 in FIG. 1.

As in the previously mentioned prior Pats. No. 2,240,429 and No. 2,793,364, the horn structure 18 is slidably mounted on the fastener inserting machine at the shelf 14 in a flanged sleeve 20. A horn bushing 22 is disposed within the sleeve 20 for transmitting upwardly directed work clamping pressure during each fastener insertion, as described at length in the aforementioned prior patents. A horn post 24 is received in turn within the bushing 22 and is engaged at a rack strip 26 thereon (compare FIGS. 1 and 2) by a pawl (not shown) carried by bushing 22, so that the horn structure 18 is allowed a range of vertical adjustment, as indicated by the full and broken line positions in FIG. 1. The top end of the horn post 24 is fitted with a flange member 28 and with an upwardly projecting axial pin 30 (see FIG. 2) on which the particular form of horn to be used is positioned. In the presently illustrated embodiment, the horn consists of post extension 32 fitted with a further axial pin 34 at its upper end (see FIG. 2) on which a horn tip member 36 is positioned as seen in FIG. 1.

Vertical adjustment of horn structure 18 is normally accomplished by grasping the flange member 28 and lifting to raise the horn tip 36 into proper work supporting relation at the operating head 10. When the proper raised position has been reached it will be held through engagement of the horn post rack 26 by the pawl carried on the horn bushing 22, while the horn structure 18 will be released for return to its lowered position by gravity simply upon releasing the pawl. Usual procedure is to place the work to be handled over the horn tip 36 at its lowered position and then raise the horn structure together with the work into proper position at the operating head. However, when a boot B is placed over the lowered horn tip 36 the depending leg portion is apt to extend downwardly far enough to cover the flange member 28 as well, so that raising of the horn structure to present the supported heel portion of the boot B at the operating head 10 is made awkward and troublesome. Subsequent lowering of the horn structure presents no problem because the pawl at the horn bushing 22 will be uncovered when the boot B has been raised, but some alternative means is needed for raising the horn structure readily when a bootleg obstructs its manipulation in usual fashion.

Such alternative means is provided according to the present invention by fitting the lower end of the horn post 24 with a stud extension 38 and mounting a lateral arm 40 thereon for lifting engagement by a pull rod 42 (see FIG. 3). The pull rod 42 is also slidably mounted on the fastener inserting machine at the shelf 14 (see FIG. 1), and is spaced in parallel relation to the axis of

the horn structure 18 at an extent sufficient to avoid interference from the leg portion of a boot B placed over the horn tip 36. The lateral arm 40 extends in correspondence with the spacing of the pull rod 42 to present an aligned aperture 44 at its projecting end through which the pull rod 42 extends to carry a split ring 46 at its lower end for engaging arm 40 at its bottom face. The result of this arrangement is to equip the pull rod 42 only for lifting the lateral arm 40 and thereby causing the horn structure to move upward through its adjustment range, while leaving the pull rod 42 free for return by gravity to a normally retracted position whenever released and to remain retracted whenever the horn structure is moved upward otherwise.

Pull rod 42 is fitted at its upper end with a knob 48 at which it may be grasped handily for lifting pull, and has a bumper flange 50 secured thereon at a suitable spacing below knob 48 to determine the normally retracted pull rod position by abutment at the top face of shelf 14. Also, the lateral arm aperture 44 is purposely made oversize and the top face of arm 42 has a felt washer 52 installed concentrically thereto to fit the pull rod diameter more closely and thereby dampen any lateral vibration tendency of the lower pull rod end during operation of the fastener inserting machine.

As thus arranged, the pull rod 42 is always available for lifting the horn structure 18 when needed. Ordinarily the pull rod 42 remains at the retracted full line position shown in FIG. 1, and allows the horn structure 18 to be manipulated in normal fashion whenever that is possible. When it is not possible, the pull rod knob 48 is adjacently available for grasping to raise pull rod 42 to the broken line FIG. 1 position and thereby lift lateral arm 40 and move horn structure 18 upwardly as also indicated by broken lines in FIG. 1. After moving the

horn structure 18 to a proper work supporting position in this way, the pull rod 42 will drop back by gravity to its retracted position and remain there until needed again.

5 The present invention has been described above for purposes of illustration only and is not intended to be limited by this description or otherwise to exclude any variation or equivalent arrangement that would be apparent from, or reasonably suggested by, the foregoing disclosure to the skill of the art.

What is claimed is:

1. In a fastener inserting machine of the type including a vertically adjustable horn for supporting work during fastener insertion, the improvement which comprises a lateral arm attached at the lower end of said horn, and a pull rod disposed in spaced parallel relation to said horn and engageable with said lateral arm for lifting the same and thereby causing said horn to move upward through its adjustment range whenever desired.

20 2. In a fastener inserting machine, the improvement defined in claim 1 and further characterized in that said horn is slidably mounted on said machine for vertical adjustment and has an axial form and extent suited for adjustment to support the heel of a boot for fastener insertion while receiving the leg of the boot thereover above said slideable mounting, and in that said pull rod is spaced from said horn sufficiently to avoid interference by said bootleg.

25 3. In a fastener inserting machine, the improvement defined in claim 2 and further characterized in that said pull rod is also slidably mounted on said machine and is arranged for engaging said lateral arm only for lifting the same so as to be free for return by gravity to a normally retracted position whenever released and to remain retracted whenever said horn is moved upward otherwise.
